(57) **CLAIM**

The ornamental design for a movable barrier operator as shown and described.

DESCRIPTION

FIG. 1 is a first perspective view of a movable barrier operator;

FIG. 2 is a second perspective view thereof;

FIG. 3 is a bottom plan view thereof;

FIG. 4 is a top plan view thereof;

FIG. 5 is a first end elevation view thereof;

FIG. 6 is a second end elevation view thereof;

FIG. 7 is a first side elevation view of the movable barrier operator; and,

FIG. 8 is a second side elevation view thereof.

Broken lines in the drawings illustrate parts of the movable barrier operator and form no part of the claimed design.

1 Claim, 4 Drawing Sheets
